UNITED STATES PATENT OFFICE.

MORRIS WINNEGRAD, OF NEW YORK, N. Y.

LADY'S GARMENT.

1,309,269.

Specification of Letters Patent.

Patented July 8, 1919.

Application filed June 8, 1916. Serial No. 102,434.

To all whom it may concern:

Be it known that I, MORRIS WINNEGRAD, citizen of the United States, and resident of New York city, in the county of New York and State of New York, have invented certain new and useful Improvements in Ladies' Garments, of which the following is a specification.

The invention relates to improvements in wearing apparel and has particular reference to a nursing waist, provided with means detachable therefrom obviating undue exposure.

The object of the invention is the providing of means adapted to be inserted in any type of stock waist or one designed for the purpose and objects of a nursing garment, said waist having fastened therein means for receiving a rubber impregnated fabric slip readily detachable therefrom for the purpose of cleaning and providing a garment inexpensive in its initial cost.

In the following is described in connection with the accompanying drawings one embodiment of the invention the features thereof being more particularly pointed out hereinafter in the claims.

In the drawings Figure 1 is an elevation of the waist showing the front placket open from the collar band; Fig. 2 is a cross sectional view on the line 2—2 of Fig. 1; Fig. 3 is a rear detail view of part of the waist and the position of the rubber impregnated slip; Fig. 4 is a vertical sectional view of the garment showing the means of attaching the impervious slip thereto, and Fig. 5 is a modified form of garment illustrating the adaptability of same as a nursing garment or dress.

Similar numerals of reference indicate similar parts throughout the several views.

In the drawings 1 indicates a waist provided with a collar band 2 and a waist band 3 and provided with the usual body sections 4 and sleeves 5. Waist 1 is provided with a placket opening 6 on one side of the bust section extending from the collar band 2 to the waist band 3, and on the opposite side of said bust section a short placket 7 extending from said collar band 2 to approximately midway or the center of the bust of the average person.

The center bust section 8 of the garment has fastened thereto on the inside studs 9 or other fastening means adapted to receive 55 eyes 10 attached to the body of a rubber impregnated fabric slip or protector 11 which is readily attachable thereto and detachable therefrom for cleansing same, and permitting the insertion of another one or the same 60 one after using, obviating the washing of the entire garment, and providing at the same time a perfect nursing garment cheap in its initial cost and one designed to prevent undue exposure while in its utilization. 65

With reference to Fig. 5 of the drawings the waist garment 1 has attached thereto a skirt 12 of any suitable design as it has been found to be applicable in many instances as the full garment is in usual demand. 70

It is obvious that the structure may be varied without departing from the spirit of the invention.

What I claim and desire to secure by Letters Patent of the United States is: 75

1. A device of the character described comprising a waist body open from the neck-band thereof to the waist-band on one side of the bust portion and from said neck-band to substantially the central body of said bust portion, a series of fastening studs attached thereto on the inside thereof adjoining said openings, a detachable rubber impregnated fabric slip, and a series of fastening eyes mounted on said slip arranged for engagement with said fastening studs on said waist body. 80

2. A device of the character described including a detachable rubber impregnated fabric slip, a series of fastening eyes mounted on the edges of said slip and a waist body provided with openings and fastening means adjacent said openings adapted to receive said slip. 90

Signed at New York city in the county of 95 New York and State of New York this 14th day of March A. D. 1916.

MORRIS WINNEGRAD.
